UNITED STATES PATENT OFFICE

162,852

REFRIGERATOR CABINET

John McLeod Little, Toledo, Ohio, assignor to
Aveo Manufacturing Corporation, Cincinnati,
Ohio, a corporation of Delaware

Application January 12, 1951, Serial No. 13,772

Term of patent 14 years

(Cl. D67—3)

To all whom it may concern:

Be it known that I, John McLeod Little, citizen of the United States of America, residing at Toledo, in the county of Lucas, State of Ohio, have invented a new, original, and ornamental Design for a Refrigerator Cabinet, of which the following is a specification, reference being had to the accompanying drawing, forming a part hereof.

The figure is a perspective view of the refrigerator cabinet in an open position, showing my new design.

The dominant features of my design reside in the portions shown in full lines.

I claim:

The ornamental design for a refrigerator cabinet, substantially as shown and described.

JOHN MCLEOD LITTLE.
